UNITED STATES PATENT OFFICE.

ALVAH BUSHNELL, JR., OF PHILADELPHIA, PENNSYLVANIA.

EXPANDING FILING POCKET.

1,403,070.

Specification of Letters Patent. Patented Jan. 10, 1922.

Application filed September 28, 1920. Serial No. 413,249.

To all whom it may concern:

Be it known that I, ALVAH BUSHNELL, Jr., a citizen of the United States, residing at Philadelphia, in the county of Philadelphia and State of Pennsylvania, have invented new and useful Improvements in Expanding Filing Pockets, of which the following is a specification.

My invention relates to a new and useful improvement in filing wallets or cases, expanding envelopes, paper pockets and the like, and has for its object to provide an expandible wallet, filing case or pocket with end flaps or wings secured to one of the sides to permit expansion of the wallet or case.

Another object of the invention is to provide in a device of the character stated flexible end flaps or wings carried by a side wall and slidably registering with a chamber or pocket in the other side wall, said end flaps or wings having non-flexible ends to prevent their accidental withdrawal from the pocket or chamber.

A further object of the invention is to stiffen the end flaps or wings throughout the major portion of their length at their inner ends to prevent accidental withdrawal from the pocket in which they are inserted and to strengthen the upper edges of said flaps; and also to provide locking means to prevent the withdrawal of the flaps or wings from the pocket or chamber.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1, is a fragmentary perspective view of a filing case or expanding wallet in a relatively closed position embodying my improvements, a portion of the end flap being broken away to plainly illustrate the construction.

Fig. 2, is a similar view showing it open or expanded.

Fig. 3, is an inner face view on a reduced

scale of the filing case opened and laid out flat.

55

Fig. 4, is an edge view thereof.

Fig. 5, is a section on the line 5—5 of Fig. 2, and

Fig. 6, is a fragmentary perspective view of a filing case or expanding wallet, a portion of the front wall being broken away to illustrate my improved device for locking the ends of the flaps or wings together while allowing a limited sliding movement therebetween.

65

Fig. 7, is a fragmentary perspective view on a reduced scale of an expanding filing case or wallet in a relatively closed position showing a slightly different construction or formation of pocket and end wings.

70

Fig. 8, is a similar view of another form of end wing.

Fig. 9, is a vertical sectional view illustrating another formation of pocket.

75

Fig. 10, is a like view of another formation.

Fig. 11, is a similar view of a further formation.

80

Fig. 12, is a similar view illustrating still another construction of pocket.

Fig. 13, is a vertical section of a wallet showing a different formation of pocket, and

85

Fig. 14, is a similar view of a variation of the last construction.

In carrying out my invention as here embodied, 2 and 3 represent the two sides or side walls of a filing case or wallet or similar device, the side 2 generally being the back and the side 3 the front. These sides are connected by an inwardly foldable or bellows bottom 4 having a bend or crease 5 to permit expanding and collapsing thereof.

90

One of the sides as 2, is provided with end flaps or wings 6, the free ends of which slidably or adjustably engage the other side 3, said side preferably being provided with a chamber or pocket 7.

The end flaps or wings 6 are flexible throughout a portion of their length, said flexible portion being sufficient to extend from one side to the other when the filing case is fully expanded, while the free ends which slide within the pocket are stiff and these stiffened ends should be longer than

100

105

the flexible portions to prevent their accidental withdrawal from the pocket so that the major portions of said end flaps or wings are stiff.

5 In actual practice the side 2 which is used as the back is made of two thicknesses of material 8 and 9 between which the end flaps or wings 6 are secured while the side 3 which become the front is made of two 10 thicknesses of material 10 and 11 throughout a portion of its height only, one of said thicknesses of material extending from the bottom to a point intermediate the upper and lower edges of the side 3 leaving the 15 upper portion of the side 3 of single thickness to form a flexible flap 12 which may be easily and readily bent forward for insertion of papers or other articles in the filing case. The two sheets or thicknesses of 20 material 10 and 11 are not attached to each other for a distance equal to the height or width of the end flaps or wings so as to form the pocket 7 in which said end flaps slide.

25 The end flaps or wings 6 may be moved in and out of the pocket by inserting the thumbs or fingers in the open ends of the pockets, but if found desirable openings 13 may be formed in the other sheet or thickness of material 11 of the side 3, one adjacent each end so that the thumbs or fingers may be pressed against the end flaps or wings to move them in either direction and this may be readily accomplished if the 35 thumbs or fingers are damped slightly.

The free or sliding ends of the end flaps or wings 6 are stiffened by attaching them to an additional sheet of thickness of material 14 which should extend throughout the 40 major portion of their length to prevent them being accidentally withdrawn when in use. The edges of the end flaps or wings 6, particularly the upper edges may be strengthened by folding a portion of the material upon itself along the upper edges of said end flaps as indicated by the reference numeral 15, Fig. 3. By constructing the end flaps in this manner the likelihood 45 of their being torn in the filing case is reduced to a minimum.

In the construction shown in Fig. 6 the end of one of the flaps 6 has a tongue 16 formed therewith terminating in a locking end 17 while the end of the opposite flap has 50 a slot 18 formed therein and adapted to receive and permit the sliding therein of the tongue 16. The tongue is inserted in this slot by folding in the projecting portions of the head, afterwards by turning these 55 ends back to their original positions the tongue will be prevented from withdrawal from the slot, thus limiting the movement of the flaps 6 and preventing their withdrawal from the pocket or chamber 7 as will 60 be readily understood.

By constructing an expanding filing case in the manner above described it is relatively inexpensive in the cost of manufacture as it eliminates the bellows end walls and skilled or experienced workers are not 70 required to produce them. This construction also provides an exceedingly strong and durable filing case which cannot be expanded beyond the limits of the flexible portions of the end flaps or wings. 75

In Fig. 7, I have shown an expanding filing case or wallet in which the sides are made of single ply material with the side wings 6^a formed as an integral part of the side wall 2, and if found desirable may be 80 provided with the stiffening material hereinbefore referred to, but which is not absolutely essential and in this form the pocket 7 is produced by superimposing a sheet of material 25 on the outside of the side wall 3 85 and securing the former to the latter along two of its opposed edges such as the top and bottom edges as indicated at 26, the ends of said superimposed sheet between these edges being free to form openings for the insertion 90 of the ends of the wings 6^a in the pocket.

In Fig. 8, I have shown the side walls 23 with the bellows bottom formed from a single thickness of material with the pocket 95 produced as in Fig. 7, while in this case the side wings 6^b are formed from separate strips of material attached to the side wall 2 at the ends thereof.

In Fig. 9, I have shown the side wall 43 100 of less height than in the other forms of my invention and utilizing an additional side wall 3^a to which the side wall 43 is secured at a point along its lower edge as at 37 and along its upper edge as at 28, the portions 105 between such points being free.

In Fig. 10, I have shown a similar construction with the addition of a strengthening strip 29 secured to the side wall 3^a and to the upper edge of the side wall 43 so as 110 to further strengthen the point of attachment of the upper edge of the wall 43 to said wall 3^a.

Fig. 11, illustrates the same construction as in Fig. 10 with the addition of an extension 115 30 of the wall 3^a folded over and secured to a portion of the bellows bottom.

In Fig. 12, the upper edge of the wall 53 is folded on itself as at 31 and attached to the wall 3^a while the lower edge of the latter wall is folded over upon itself as at 32 and attached to the wall 53. 120

The construction shown in Fig. 13 has the pocket 7 formed between the side wall 63 and the coating wall 3^a with the latter 125 folded over and secured to the bellows fold or bottom 4 as in Fig. 11, but the upper edge of the side 63 is free from the wall 3^a so that access may be had to the pocket from the inside of the wallet and is normally closed by 130

a flap 33 secured to the inside of the wall 3^a which hangs down over the side 63. This flap also prevents papers or articles from entering the pocket when being placed in 5 the wallet.

The above construction may be slightly varied, as shown in Fig. 14 by providing the side wall 73 with a slot or opening 84 for the insertion of the free end of the flap 83 10 which will eliminate any projecting ends within the wallet compartment.

It is to be understood that the different constructions here illustrated and described are interchangeable so that the different 15 pocket formations can be used with any one of the different forms of side wings and the latter may or may not be provided with interlocking devices and stiffening elements.

Of course I do not wish to be limited to 20 the exact details of construction as herein shown as these may be varied within the limits of the appended claims without departing from the spirit of my invention.

Having thus fully described my invention, 25 what I claim as new and useful is:—

1. A filing case including sides one of which is provided with a pocket, end flaps or wings carried by one of the sides and having non-flexible ends slidably mounted in the pocket. 30 2. A filing case or wallet including sides, one of which is provided with a pocket open at both ends and having openings communicating with said pocket, end flaps or wings carried by one of said sides entering the 35 pocket through the open ends, said end flaps having stiff ends to prevent their accidental withdrawal from the pocket.

3. A filing case or wallet including sides, one of which is provided with a pocket, end 40 flaps or wings carried by one of the sides the ends of said flaps projecting into said pocket, and means for securing said ends together so as to permit a limited sliding movement thereof.

45 4. In a filing case including sides, one of which is provided with a pocket, end flaps of wings carried by one of the sides and

having their ends adapted to form a slip joint received in said pocket for securing the ends together while allowing a limited sliding movement thereof.

5. A filing case including sides, one of which is provided with a pocket, flaps carried by the other of the sides, the ends of said flaps projecting into said pocket, a 55 tongue and locking head formed upon one of said flaps adapted to engage the end of the opposite flap so as to have a limited movement therein.

6. A filing case including sides one of 60 which is provided with a pocket and end flaps or wings carried by the other side with the free ends slidably mounted in the pocket.

7. A filing case including sides connected 65 with an expansible bellows fold and end wings carried by one of the sides and registering with a pocket carried by the other side.

8. A filing case including sides one of 70 which is provided with a pocket, a bellows fold connecting said sides and end flaps or wings carried by one of said sides slidably mounted in the pocket.

9. A filing case including single ply sides, 75 one of which is provided with a pocket, wings attached to one of said sides and having their free ends slidably mounted in the pocket.

10. A filing case including sides, a sheet 80 of material disposed across one of said sides secured thereto along two opposed edges leaving the same free between said edges to form a pocket open at opposite ends, and wings carried by the other side with the free 85 ends slidably mounted in said pocket.

11. A filing case including sides, and another wall disposed across one of said sides attached thereto along two opposed lines with the material between being free to form 90 a pocket.

In testimony whereof, I have hereunto affixed my signature.

ALVAH BUSHNELL, JR.
